UNITED STATES PATENT OFFICE.

LOUIS H. MARTELL, OF ELYRIA, OHIO.

PACKING DEVICE.

1,272,288.

Specification of Letters Patent.

Patented July 9, 1918.

Application filed January 30, 1914, Serial No. 815,383. Renewed May 3, 1918. Serial No. 232,384.

To all whom it may concern:

Be it known that I, LOUIS H. MARTELL, a citizen of the United States, residing at Elyria, in the county of Lorain and State 5 of Ohio, have invented a certain new and useful Improvement in Packing Devices, of which the following is a full, clear, and exact description.

This invention relates to a device for 10 packing a pump plunger. In the particular form of the device herein illustrated, it is applied to packing a plunger extending between opposed cylinders of a pump.

The object of the invention is to provide 15 a device which will effectively prevent the seepage of water or other fluid material along the plunger, as it reciprocates.

In general, the invention comprises the 20 elements and their combinations as defined by the accompanying claims.

Reference should be had to the accompanying drawings forming a part of this specification, in which Figure 1 is a side elevation with portions in section; Fig. 2 25 is a sectional elevation on the line 2—2 of Fig. 1; Fig. 3 is an elevation with portions in section of a modified form of my device; and Fig. 4 is a section along the line 4—4 of Fig. 3.

The opposing cylinders of a pump are indicated at 1 and 2, and the plunger which extends between the cylinders of the pump is indicated at 3. The cylinder head 1 is recessed, and is adapted to receive a sleeve 30 4, which has an easy fit in the recess. This cylinder contains a packing 4^a, which engages with the piston rod. At its forward end, the sleeve 4 is beveled.

Ahead of the sleeve 4 is a sleeve 5, which 40 at its inner end is beveled, thereby forming a groove between the sleeves 4 and 5. In this groove is a packing 6, which lies against the surface of the recess formed in the head 1, the packing 6 being compressed as the 45 sleeve 5 is moved toward the sleeve 4.

The sleeve 5 is provided with a flange 7 at its forward end, which is provided with two series of threaded openings, the function of which will be stated a little later on.

The cylinder head 2 is recessed in a manner similar to that described with respect to cylinder 1, and receives a sleeve 8, packing 9, in exactly the same manner as that heretofore described with respect to the 55 sleeve 4.

A sleeve 10 having its inner end beveled,

engages the packing 9, to compress the same in the same manner as does the inner end of the sleeve 5. Between the plunger and the sleeve 10 is a packing 11.

The sleeve 10 is provided with an extending portion 12, which is of proper diameter to fit within a recessed portion 13 of the sleeve 5,—the fit between the extending portion 12 and the sleeve 5 being such that the 65 sleeves 5 and 10 may be readily moved relatively to each other.

Upon the extending portion 12 of sleeve 10 there is a compressing member 14, the diameter of which is such as to readily slide 70 within a recessed portion 15 of sleeve 5. Ahead of the compressor member 14 is packing 16 which is adapted to be compressed, as the compressor member 14 is moved toward the sleeve 5.

The compressor member 14 has a flanged head 17 through which extend a plurality of threaded bolts 18, the said bolts extending into certain of the threaded openings in the head 7 of the sleeve 5. Manipulation of 80 these bolts 18 draws the compression member 17 toward the sleeve 5, and thereby compresses the packing 16.

The sleeve 10 is provided with a head 10^a, and between the head 10^a and the head 7 there extends threaded bolts 19, these bolts 85 engaging with certain of the threaded openings in the head 7, while the heads of the bolts engage with the head 10^a. The bolts 19 pass through the openings 20, which are 90 formed with the head 17 of the compressor member.

Adjustment of the bolts 19 will cause the sleeves 5 and 10 to move away from each other, thereby compressing the packing 6 95 and 9, which is carried adjacent the sleeves 4 and 8 respectively.

It will be seen from the foregoing description that it will be impossible for any liquid to pass between the packing and plunger, 100 as it reciprocates. The packing 6 and 9, together with the packing 15 may be suitably compressed by the manipulation of the bolts 18 and 19, so as to tightly seal all possible sources of exit for the fluid.

In Figs. 3 and 4, there is shown a slightly modified form of the device of my invention.

In these figures, the heads of the opposing cylinders are indicated at 20 and 21. These cylinders are recessed. Within the recess of 110 the cylinder head 21 there extends a sleeve 22, which at its inner end is provided with a

beveled portion that engages with a packing 23. The packing also engages the end and outer side of the recess in the cylinder 21 so that as the sleeve 22 is moved inwardly 5 the packing 23 will be compressed.

The sleeve 22 is formed to have a sliding fit in the recess of the head of the cylinder 21, and also to have a sliding fit upon the piston 3. The sleeve 22 is provided with 10 water grooves 22^a.

The cylinder head 20 is provided with a groove which receives a sleeve 24 and packing 25 that operates in the same manner as that just described with respect to sleeve 22.

15 The sleeves 22 and 24 extend slightly beyond the face of their respective cylinders. Sleeve 22 coöperates with a sleeve 26. The engaging faces of these sleeves have a ground fit, thereby preventing the escape of any 20 fluid between them.

This sleeve 26 is provided with a recessed portion 26^a and with a head 27 which contains two sets of screw threaded openings.

A sleeve 28 extends along the plunger 3, 25 and has within it a packing sleeve 29. The sleeve 28 is provided with a head 30.

The sleeve 28 extends within the recessed portion 26^a of the sleeve 26, and at its inner end supports a ring 31. This ring is of 30 suitable diameter to fill the grooves between the sleeve and the outer wall of the groove 26^a.

Upon the sleeve 28 are packing elements 32 which are adapted to be engaged by a 35 compressing member 33. This compressing member fits upon the sleeve 28 and within the outer part of the groove 26. This compressing member 33 has a head 33^a, with which coöperates bolts 34 which are adapted 40 to engage with certain of the screw threaded openings in the head 27. These bolts when tightened, draw the compressor member toward the head 27 and thereby compress the packing 32.

45 Between the head 30 and the sleeve 24 is a two-part sleeve 35 containing suitable packing, the parts of the sleeve being held together by a bolt 36. The engaging faces of the sleeves 24 and 35, as well as the engaging 50 faces of the sleeve 35 and the head 30, are ground to fit, thereby preventing the escape of fluid from the plunger 3.

Bolts, one of which is indicated at 37, engage in certain of the threaded openings 55 in the head 27 and at their opposite ends bear against the head 30. These bolts extend through slotted openings 38 in the head 33^a of the compressor member. Manipulation of the bolts 37 will cause the heads 60 27 and 30 to be pushed apart, thereby compressing the packing 23 and 25 to form a seal to prevent the escape of fluid at these points, and the packing 32 will effectively prevent the escape of fluid between the 65 sleeves 28 and 26.

Having thus described my invention, what I claim is:

1. The combination with opposed cylinder heads and a plunger operating between them, a packing device surrounding the 70 plunger and extending between the said heads, said device comprising opposed sets of sleeves, packing between the sleeves of each set, the sleeve of each set which is adjacent the cylinder heads being surrounded by 75 a portion of the cylinder and with which the packing between the sleeves in each set may engage, and rigid means for moving the adjacent sleeves of said sets of sleeves in opposite directions. 80

2. The combination with opposed cylinder heads which are recessed, and a plunger operating between said heads, of a packing device surrounding the plunger and extending between the cylinder heads, said packing 85 device comprising sleeve elements adapted to be seated within the recesses in the cylinder heads, opposed sleeve members upon said plunger, packing associated with the sleeve elements within the recesses of the cylinder 90 heads, means for moving the opposed sleeve elements upon the plunger to compress the packing associated with the sleeves in the cylinder heads, and packing between the opposed sleeves. 95

3. The combination with opposed cylinder heads, and a plunger operating between them, of a packing device surrounding the plunger and extending between the said heads, said packing comprising opposed sets 100 of sleeves, one set of sleeves being provided with an extended cylindrical portion, the other of said sleeves surrounding said cylindrical extending portion, means for moving adjacent sleeves of said sets in opposite 105 directions, and a packing means between the extending cylindrical portion of one sleeve and the sleeve which surrounds said cylindrical portion. 110

4. The combination with opposed cylinder heads, and a plunger operating between them, of a packing device surrounding the plunger and extending between the said heads, said packing comprising opposed sets of sleeves, one set of sleeves being provided with an extended cylindrical portion, the other of said sleeves surrounding said cylindrical extending portion, means for moving adjacent sleeves of said sets in opposite directions, and a packing means between the extending cylindrical portion of one sleeve and the sleeve which surrounds said cylindrical portion, and means for compressing 115 said packing. 120

5. The combination with opposed cylinder heads, of a plunger operating between the said cylinder heads, recesses in the cylinder heads surrounding the plunger, sleeves fitting within said recesses, packing associated with said sleeves, a sleeve surrounding the 125 130

- plunger adapted to coöperate with one of the above mentioned sleeves, to compress the packing associated therewith, said sleeve being provided with a forwardly extending portion of reduced diameter, a second sleeve surrounding the piston rod and adapted to coöperate with the other of the above mentioned sleeves within the recess of the cylinder head, to compress the packing associated therewith, the said sleeve upon the plunger being provided with a recess adapted to receive the extending portion upon the other of said sleeves, packing members between the grooved sleeve and the forwardly extending portion upon the other of said sleeves, a compressor member adapted to compress the said packing, and means for securing longitudinal adjustment of the sleeve surrounding the piston rods.
6. The combination with the heads of opposed cylinders, and a plunger extending between the said cylinders, the said cylinder head being formed with recesses which surround the plunger, sleeves within the said recesses, packing associated with each of said sleeves, means adapted to coöperate with the sleeves within the recessed portions of the cylinder head for effecting compression of the said packing, said means comprising a recessed sleeve provided with a head, a compressor member, packing within a portion of said recessed sleeve, and engaged by the compressor member, means for adjusting the compressor member, a second sleeve provided with an extending portion, which extends within the first mentioned recessed sleeve, and expanding members associated with both of the last mentioned sleeves to adjust them longitudinally of the plunger.
7. The combination with opposed cylinder heads and a plunger operating between said heads, of a packing device surrounding the plunger and extending between the cylinder heads comprising sleeve elements adjacent the heads of the cylinders, packing associated with the sleeves adjacent the cylinder heads, opposed sleeve elements upon the plunger between the first mentioned sleeve elements, and means for moving the opposed sleeve elements upon the plunger to compress the packing associated with the sleeve elements adjacent the cylinder heads, and packing between the said opposed sleeve elements.
8. The combination with opposed cylinder heads and a plunger operating between said heads, of a packing device surrounding the plunger and extending between the cylinder heads, comprising sleeve elements adjacent the heads of the cylinder heads, packing associated with said sleeve elements, opposed telescoping sleeve elements upon the plunger between the sleeve elements adjacent the cylinder heads, means for relatively moving the telescoping sleeve elements to compress the packing associated with sleeve elements adjacent the cylinder heads, packing between the telescoping sleeve elements, and means for compressing the last mentioned packing.

In testimony whereof, I hereunto affix my signature in the presence of two witnesses.
